UNITED STATES PATENT OFFICE.

ALFRED EDWIN BAWTREE, OF SUTTON, ENGLAND, ASSIGNOR OF ONE-FIFTH TO
SYDNEY E. PAGE, OF LONDON, ENGLAND.

PHOTOGRAPHIC TYPE-COMPOSING MACHINE.

1,283,394.

Specification of Letters Patent. Patented Oct. 29, 1918.

Application filed December 27, 1915. Serial No. 68,948.

To all whom it may concern:

Be it known that I, ALFRED EDWIN BAWTREE, subject of the King of Great Britain, residing at Sutton, England, have invented 5 new and useful Improvements in Photographic Type-Composing Machines, of which the following is a specification.

This invention relates to photographic type-composing machines.

10 One object of the invention is to simplify and improve the construction and operation of that class of type-composing machine in which the characters are impressed by means of light upon a photographic surface, such 15 improvement simplifying the mechanism but at the same time increasing the scope of usefulness of the machine.

Other objects of the invention will appear more fully hereafter.

20 The invention consists in the construction, combination, location, and arrangement, all as will be more fully hereinafter set forth, as shown in the accompanying drawings, and finally pointed out in the appended claims.

25 Referring to the accompanying drawings, and to the various views and reference signs appearing thereon, Figure 1 is a front elevation of the machine with parts of the mechanism removed in order to show other 30 portions, Fig. 2 is a side elevation of the whole machine similarly treated, Fig. 3 is a section of the sensitive material roll holder, Fig. 3^a is a side view of the sensitive material holder, Fig. 4 is a plan of the whole 35 machine, Fig. 5 is a diagram illustrating the peculiar arrangement of the characters upon the negative disk, Fig. 6 similarly shows in diagrammatic form the automatic focusing mechanism, Fig. 6^a shows as an addition to Fig. 6 the proportionate lever connection for obtaining uniform illumination, and Fig. 7, shows the pneumatic switch to an enlarged scale.

The same part is designated by the same 45 reference sign wherever it occurs throughout the several views.

The negative containing the characters is of the well known disk form, but I arrange each character in a special manner. One 50 side of the character touches a radius of the circle, while the base line of each member of a set of characters is a tangent to a common circle. The value of this special arrangement lies in the fact that by so ad-

justing the optical parts of the machine that 55 these two boundary lines of each character fall into the two planes which intersect along the axis of the lens, the characters will always aline and space perfectly, no matter how the scale of enlargement or reduction 60 may be varied, even if such variation occurs in the middle of a word. As in previous inventions of this nature there may be one or more rings of characters upon each negative disk.

65 The machine is of that type in which a lens is employed to project the image of the character upon the sensitive surface, as distinguished from the form in which the impression is received by contact of the one 70 with the other. The machine thus consists of the three parts:—

- (a) The negative disk and its attachments.
- (b) The lens and its attachments.
- (c) The sensitive surface and its attach- 75 ments.

These three are all geared together in such a manner that, by operating a single pointer, lever or other convenient attachment, the scale of enlargement or reduction of the 80 image, thrown by the lens upon the sensitive surface, can be altered at will and, at whatever point the mechanism is set, the image projected by the lens will always be in focus upon the sensitive surface.

85 In operating the machine the following adjustments are necessary:—

- (d) Setting the scale of enlargement or reduction.
- (e) Bringing the desired ring of characters into position, when there is more than one ring upon a negative disk.
- (f) Bringing the correct character upon a ring into position.
- (g) Bringing into position to receive the 95 image the portion of sensitive film, whose size is determined by the features of the spacing cam.
- (h) Making the photographic exposure in any suitable manner.
- (i) At the end of a line, bringing a fresh portion of the sensitive surface into position.
- (j) Making the register marks upon the material and the marks to distinguish be- 105 tween the lines.

The invention consists in a simple and effective construction and inter-connection of

parts whereby the results mentioned are secured, and which will now be described more in detail.

Referring to the drawings A is the negative disk holder, consisting of a plate with openings in it, A², through which the characters upon the negative disk can be illuminated. Around its edge are two rows of holes, B¹, B², which correspond to the positions of the characters upon the negative disk. Rings of characters are marked around this disk, readable by means of the pointer A¹, indicating roughly which character upon the negative disk is opposite the lens.

C is the negative disk, fitted behind the disk holder A.

D is a pointer which can enter any one of the holes in B', thus anchoring any desired character accurately in position.

E is the spindle upon which A is mounted. It passes through a block F, capable of adjustment in vertical slides I by means of the levers G¹, G². These levers are operated by means of a pedal o, connected to them by the chain G³, and the upper or lower positions of the block F bring into the field of the lens the outer or inner ring of characters upon the negative disk C respectively and, with each ring of characters, the ring of holes in A corresponding to it is brought opposite the point of D.

H is the spacing cam fitted upon the other end of the spindle E. The pins H¹, H², H³, &c., upon its face are cut short of a zero length to an extent just equal to the width of a character to which it corresponds. Thus if the zero length is 15 mm. and the width of a particular character is 6 mm., the pin relating to that character will have 6 mm. cut off it and in consequence will stand out 9 mm. from the face of the spacing cam H. Similarly for a character 12 mm. wide, the pin will only stand out 3 mm.

J is a disk, graduated upon its upper face with the scale of enlargement or reduction to which it is desired to set the machine. It can be locked in any position by means of the point J¹, which passes through suitably placed holes near its circumference. On the under side of J, a pin J⁵ operates the connecting rod J², which at its other end slides the sensitive material roll holder carriage R along the center rail of the machine M.

A cam J³, also attached to the under side of J, winds up or pays out a ribbon J⁴, which regulates the motion of the lens standard L. This ribbon is kept taut by any suitable mechanism, such as a spring x connecting the roll holder carriage R with the lens standard L. By reason of the pin J⁵ having to pass the dead center in order to reach a similar position on the other side of the center line, it will be seen that a reciprocating motion is imparted to the roll holder

carriage R, while for the same travel a continuous motion only of the lens standard L is involved. Such different motions are required by the optical properties of the lens.

Some means such as a proportionate lever connection of the source of light W² to the lens W¹ is used to obtain uniformity of illumination; conveniently this may be done by means of the lever system shown in Fig. 6^a. The electric circuit from the wires g and h passes through a source of current and then through the lamp W². The light from this lamp shines through the condenser lens W¹. The lamp W² is mounted on a block W³, which is capable of movement parallel to that of the block M¹.

Upon M¹ and W³, are pins which engage in the slotted ends of the levers W⁴ and W⁵ respectively. These levers are pivoted about the fixed fulcrums W⁶ and W⁷ respectively, and are connected together at their other ends by the link W⁸. It is therefore evident that by suitably fixing the positions of the fulcrums W⁶ and W⁷, the motion of W² will be proportional to the motion of M¹ to any desired scale of reduction. Intensity variation of the light may be obtained by any well known means, such as an iris diaphragm, or a variable resistance in the electrical circuit of the lamp.

K is a frame containing two spools between which a spool of flexible film, bearing a series of negatives of suitable tints, can be wound by means of the milled heads K¹. It is mounted upon the graduated tube K², which can be rotated and clamped in the slit ring K³. Thus any tint along the film can be brought opposite the lens and each tint can be set at an angle.

L is the lens standard, which slides along the central rail M by means of the sleeve M¹, the side rail N serving as a guide to prevent the rotation of the sleeve. A bracket on the lens standard supports the pin L¹, whose axis is in the same plane at right angles to the axis of the lens as the nodal point of the lens L². This pin forms the fulcrum of the letter spacing lever L³. It should be explained that it is important to use a lens in which the two usual nodal points coincide, or so nearly coincide that they may be counted as one point. It is through this point, between them if there are two, and equidistant from each, that the plane is taken in which lies the axis of the fulcrum pin.

The handle P is suitably connected to the coarse threaded screw P¹ in such a manner that rotating the handle P moves the wedge P² backward or forward. This wedge presses against the sliding rod P³, against the other end of which presses the surface of the lever L³. The lever P⁴, pivoted about the fixed fulcrum P⁵, swings in or out following the reciprocating motion of the threaded cylin-

der P^1 formed integrally with the double walled space P^7 , which embraces the end of control lever P^4 . The other end of the lever P^4 is limited in its motion by the end of the pin on the spacing cam with which it comes in contact, this pin being the one in position for the particular character about to be photographed. The lengths of lever and angle of wedge are so arranged that the point upon the lever L^3 which is in contact with the rod P^3 has a transverse motion equal to a constant amount plus the width of the character upon the negative disk, as represented by the lack of length of its particular spacing cam pin. The parts are also so placed that the point at which P^3 engages L^3 is in the plane of the negative disk C . Operated by the sliding rod P^3 is a suitable pneumatic electric switch P^6 , which, however great or small may be the motion of P^3 beyond a zero amount, always connects the current for a fixed time. This movement is obtained as follows:—The movement of the rod P^3 imparts motion to the lever L^3 , thereby pushing back the head b of the spring rod a . The head b terminates below in the fork c , in which is pivoted the end of the piston rod d . The piston head is provided with the leather cup j as in an ordinary cycle pump, whereby it is only air-tight when moving to the left.

The zero motion imparted to P^3 suffices to carry the cup j clear of the circle of holes k . These holes prevent any air compression from taking place on the return of the piston to the left until it has reached them. By that time all the motion due to the spacing cam pin will have been used up, the remaining motion to the left being due to the zero motion referred to hereinafter.

When j reaches k the lower edge of the fork c reaches the metal plate f , which is mounted on the insulating bracket e and connected to the wire g . The other wire h is connected to the general metal work of the machine and therefore to c . The electric circuit is therefore closed for as long as the fork c is scraping over the plate f , which may be any amount up to the remaining travel of j after reaching k .

The casing of P^6 terminates in the screw cap l , which holds the thin metal diaphragm m in position. In the center of this diaphragm is a small hole which is adjusted to cause the compressed air to escape from the interior of P^6 at the desired rate. The length of photographic exposure is therefore controllable by adjusting the size of this hole, or by the length of f . The zero motion is the minimum motion, represented by that obtained when a pin of the spacing cam is of full length, that is equivalent to a space before the letter on the negative disk is allowed for at all. Thus, whatever the width of a letter be, the electrical exposure is always the same. The electric current is con-

nected with the electric lamp W^2 whose light shines through the openings A^2 in the disk A and thence through the character in the negative disk which is to be exposed. The parts are so arranged that turning the handle P , as far as it will go one way, operates the lever L^3 and sets the pneumatic switch, while the return of the handle P to its original position releases the pneumatic switch, so making the photographic exposure.

The sensitive material roll holder Q slides transversely across the machine on the rails R^1 , R^2 of the carriage R . This carriage runs on the rail M by means of the sleeve R^3 and is guided by the side rails N and O . Passing through the base of the roll holder are the ratchet rods Q^1 , Q^2 . Q^1 is fixed at its ends to the ends of the carriage R . Q^2 terminates in the vise Q^3 , the opening of whose jaws is adjustable by the micrometer screw Q^4 . This vise spans the portion of the lever L^3 which is in the plane of the sensitive material Q^6 in the roll holder Q . Thus the exact amount of the motion of the lever at this point will be the motion imparted to the sensitive material. Therefore, on account of the fact that the fulcrum of this lever L^3 is in the plane at right angles to the axis of the lens and containing the nodal point of the lens, it follows that the motion imparted to the sensitive material will be the exact multiple of the lack of length of the spacing cam pin, plus the constant amount of motion already referred to, so that the size of the image on the sensitive material is of the size of the character upon the negative disk. The object of the micrometer screw and scale Q^4 is to permit more or less motion of the roll holder Q in addition to that due to the dimensions of the spacing cam pins. It has been noted that P^3 imparts to the point of L^3 with which it is in contact a degree of motion equal to the lack of length of the spacing cam pin, plus a constant amount. With the screw Q^4 fully out, this constant amount will be taken up, even when the machine is set to its fullest extent of enlargement, while, when the screw of Q^4 is screwed right home, the

whole of the motion of the rod P^3 is imparted to the roll holder Q , augmented or diminished according to the position of the lever L^3 . By means of this arrangement of parts it is possible to determine any desired amount of space between the characters to be impressed upon the sensitive surface in addition to the zero amount provided for by the spacing cam pins. The amount of space between characters, as set by the vise Q^3 and the micrometer Q^4 , is absolute, that is to say it does not vary according to differences of enlargement or reduction. It may be made, however, to vary in any desired manner by varying the width of the lever L^3 . Spacing which shall be augmented or re-

duced in conformity with the scale of enlargement or reduction can be provided for by limiting the backward motion of any of the traversing parts between the handle P and the sliding rod P³, say, for example the threaded cylinder P¹.

The ratchet rods Q¹, Q² pass between pawls V¹, V², Q¹ being a fixed rod and Q² moving the carriage R along R¹, and R², by means of the pawl V², while the pawl V¹ prevents its return. Pins Y moving in the V slot V³ cause both these pawls to open when the pawl holding frame V is pushed in a direction toward the rods, thus allowing the roll holder carriage R to be returned to the commencement of its travel for starting a new line.

A suitable electric or other alarm Q⁵ can be fitted to the roll holder Q or its attachments. In Fig. 4 it is shown mounted upon the ratchet rod Q¹. By means of this device warning can be given when the roll holder Q has arrived at or near the end of its travel.

The sensitive material is wound forward to receive a new line of characters by turning the divided head S, which operates the milled rollers S¹, S². The shield T¹ on the lever T covers this divided head S and prevents it from being read until the lever T is pulled back as shown in Fig. 2. Pulling back this lever pushes forward the ratchet rod pawl holder V by reason of the lever T¹⁰ connected to such holder turning about the pivot Z. Releasing the lever T causes it to come forward under the pull of the spring T², thereby throwing the pawls V¹, V² into action and simultaneously preventing the disk S from being further read. The forward motion of this lever T also drives the punches T³ in the dies T⁵ through the sensitive material Q⁶, and at the same time brings the automatic numbering wheel T⁷ into contact with the back of the sensitive material Q⁶.

The numbering device is merely the ordinary type numbering stamp in common use adapted to work with its plunger connected to the punch T⁸, or with its plunger operated by means of a separate lever on the spindle Z; as it is well known it is not illustrated, other than diagrammatically as regards its number wheel T⁷, in order not to confuse the drawings.

As will be seen from Fig. 3^a of the drawings the dies T⁵ and the punches T³ are in duplicate, one operating at each end of the composed line.

The course of the procedure therefore in operating the machine is as follows. Having charged the sensitive material roll holder with material and attached the required negative disk C to the holder A, adjust the divided disk J to the scale of enlargement or reduction required. Turn the disk A till the required character is oppo-

site the pointer A¹, while holding back the spring point D. Release this point D when the character will be accurately locked in position. Turn the handle P as far as it will go and release it. When it has returned to its original position, the exposure is completed and the cycle of operations can be repeated till the alarm Q⁵ indicates that a line is completed. Pull back the lever T by pinching together the pin T⁸ on the lever 75 and the pin T⁹ on the side of the roll holder, as shown in Fig. 2. While doing so, first pull the roll holder Q forward as far as it will come and then turn the disk S the amount needed to bring a fresh line of sensitive material into position.

The whole machine being an instrument of precision, provision is made whereby bolting it down to a bench does not distort it. To this end the whole machine rests upon the three spherical feet U, Fig. 1. Two as shown in this figure are under the front of the machine and the third is at the back. The bolts U¹ pass through sleeves U², which are too long and therefore do not permit the machine to be clamped down tightly. Moreover the holes U³ are larger than the sleeves U². As a result the machine is anchored but at each point has a small amount of movement in every direction.

It must be clearly understood that the above describes a representative form of the invention and that modifications will be necessary if other sensitive film carriers than rolls are employed.

While, therefore, I have shown and described various specific constructions and arrangements as operative embodiments of the principles of my invention, I do not desire to be limited or restricted thereto; but,

Having now set forth the object and nature of my invention and forms of apparatus embodying the same and having explained its construction, function, and mode of operation, what I claim as new and useful and of my invention, and desire to secure by Letters Patent is:—

1. In a photographic type-composing machine, the combination with a negative disk, a camera, and a movable sensitive material holder, of a spacing cam, pins thereon of a length dependent upon the width of a corresponding character on the negative disk, and means connecting the said pins with the sensitive material holder whereby the latter is moved a distance varying as the length of a particular pin when the machine is operated to photograph that particular character, substantially as described.

2. In a photographic type-composing machine, the combination with a negative disk, a movable lens carrier, and a movable sensitive material holder, of a spacing cam, pins thereon of a length dependent upon the width of a corresponding character on the

- negative disk, means connecting the said pins with the sensitive material holder, and a crank and cam mechanism for connecting together the negative disk, the lens carrier and the sensitive material holder whereby a single movement of the crank will vary the scale of enlargement or reduction effected by the optical system to any desired degree while preserving the correct focusing of the optical system, and the correct spacing for the enlarged or reduced characters.
3. In a photographic type-composing machine, the combination with a negative disk, a movable lens carrier, and a movable sensitive material holder, of a spacing cam, pins thereon of a length dependent upon the width of a corresponding character on the negative disk, means connecting the said pins with the sensitive material holder, a crank and cam mechanism for connecting together the negative disk, the lens carrier and the sensitive material holder, and means whereby the movement of the crank for varying the size of the character simultaneously adjusts the illuminating system to give correct results as regards both uniformity and intensity of illumination, with a constant duration of exposure.
4. In a photographic type-composing machine of the class described the combination of a negative disk, a fixed support for same, a disk and cam pivoted thereon, a sensitive material holder, a carriage therefor, a lens carrier, a connecting rod from the disk to the said carriage, and a spring-controlled flexible connecting element from the said cam to the lens carrier, substantially as and for the purpose set forth.
5. In a photographic type-composing machine, the combination with a negative disk, a camera, and a movable sensitive material holder, of a spacing cam, pins thereon of a length dependent upon the width of a corresponding character on the negative disk, a longitudinal spacing lever, a pivot fulcrum therefor whose axis is in the same plane at right angles to the axis of the lens as the nodal point of the camera lens, a transverse rod and pawl connecting one end of the spacing lever with the sensitive film so as to operate in the plane of the said film, a wedge and rod connection to the longitudinal lever on the other side of its fulcrum with the rod sliding transversely in the plane of the negative disk, means for reciprocating the said wedge, and a lever operating between the pins of the spacing cam and the reciprocating wedge to control the amount of movement of the latter.
6. In a photographic type-composing machine of the class described, and in combination, a rotary handle and a spindle, a fixed frame supporting same, double walls on the spindle forming a space intermediate of its length, a threaded cylinder at one end thereof, a sliding wedge connected thereto, means for preventing rotation of the wedge, pins on the fixed frame engaging the threads of the cylinder, and a controlling lever working between the double walled space and the pins of the spacing cam.
7. In a photographic type-composing machine, the combination with a negative disk, a movable lens carrier, and a movable sensitive material holder, of a spacing cam, pins thereon of a length dependent upon the width of a corresponding character on the negative disk, a fixed support for the negative disk, a disk and cam pivoted thereon, a connecting rod from the disk to the carriage of the sensitive material holder, a spring controlled flexible connecting element from the cam to the lens carrier, a longitudinal spacing lever, a bracket on the lens carrier extending transversely of the machine and having a fulcrum for the spacing lever at its outer end, a transverse rod and pawl connected to the sensitive material holder and having a vise engaging one end of the spacing lever, a wedge and sliding rod connection to the other end of the spacing lever, means for reciprocating the wedge, and a lever controlling said means by engaging the pins of the spacing cam, all substantially as and for the purpose set forth.
8. In a photographic type-composing machine of the class described, and in combination, a spacing lever, a vise, a scale and a micrometer screw threaded in one jaw of the said vise so as to engage one end of the said lever, a sensitive material holder, and a rod connecting the sensitive material holder with the vise so as to form the opposite jaw of the vise, substantially as and for the purpose set forth.
9. In a photographic type-composing machine, a negative disk having its characters arranged with their base lines tangential to one or more common circles and one side of each character touching a radius of the circle to which it belongs.
10. In a photographic type-composing machine, the combination with a negative disk, a camera, and a movable sensitive material holder, of a spacing cam, pins thereon of a length dependent upon the width of a corresponding character on the negative disk, means connecting the said pins with the sensitive material holder whereby the latter is moved a distance varying as the length of a particular pin when the machine is operated to photograph that particular character, an electric switch and means operated by the last named mechanism to work same whereby the photographic exposure is subsequently made automatically.
11. In a photographic type-composing machine, the combination with a negative disk, a movable lens carrier, and a movable sensitive material holder, of a spacing cam,

pins thereon of a length dependent upon the width of a corresponding character on the negative disk, a crank and cam mechanism connecting together the negative disk, 5 the lens carrier, and the sensitive material holder, means connecting the pins of the spacing cam with the sensitive material holder, an electric switch and means operated by the last named mechanism to work 10 same whereby the photographic exposure is subsequently automatically made and with a constant duration of exposure although the spacing movement may vary in extent.

12. In a photographic type-composing machine, the combination with a negative disk, a camera, and a movable sensitive material holder, of a spacing cam, pins thereon of a length dependent upon the width of a corresponding character on the negative disk, means connecting the said pins with the sensitive material holder whereby the latter is moved transversely, manual means provided with a divided head moving the sensitive material within its holder at right angles to its transverse movement, a spring-controlled lever, a shield thereon partially covering the divided head, and means operated by the movement of the said lever for perforating each composed 20 line on the sensitive material to assist in subsequently cutting the said lines accurately apart.

13. In a photographic type-composing machine, the combination with a negative disk, a movable lens carrier, and a movable sensitive material holder, of a spacing cam, pins thereon of a length dependent upon the width of a corresponding character on the negative disk, means connecting the said pins with the sensitive material holder so as to move the latter transversely, a crank and cam mechanism for connecting together the negative disk, the lens carrier and the sensitive material holder, manual means provided with a divided head moving the sensitive material within its holder at right angles to its transverse movement, a spring-controlled lever, a shield thereon partially covering the divided head, and means operated by the movement of the said lever for perforating each composed line on the sensitive material and at the same time actuating a type numbering stamp for numbering the lines distinctively.

14. In a photographic type-composing machine, the combination with a negative disk, a camera, and a movable sensitive material holder, of a spacing cam, pins thereon of a length dependent upon the width of a corresponding character on the negative disk, means connecting the said pins with the sensitive material holder whereby the latter is moved transversely, manual means provided with a divided head moving the sensitive material within its holder at right angles to

its transverse movement, a spring-controlled lever, a shield thereon partially covering the divided head, and means operated by the movement of the said lever for releasing the automatic transverse movement connection 70 whereby the return transverse movement may take place.

15. In a photographic type-composing machine, the combination with a negative disk, a movable lens carrier, and a movable sensitive material holder, of a spacing cam, pins thereon of a length dependent upon the width of a corresponding character on the negative disk, means embracing a longitudinal spacing lever connecting the said pins with the sensitive material holder so as to cause a transverse movement thereof, a crank and cam mechanism for connecting together the negative disk, the lens carrier, and the sensitive material holder, means for disconnecting the sensitive material holder from the longitudinal spacing lever and bringing the sensitive material into position to receive the commencement of a new line, means simultaneously operated by the last 85 mechanism to perforate a line, and means similarly operated to number the line.

16. In a photographic type-composing machine of the class described, the combination with a sensitive material holder, of a pair of rollers engaging the sensitive film, a graduated disk attached to the end of one of the rollers so that said roller may be rotated thereby, the amount of film moved forward being indicated by the said graduations, film 100 perforating punches, a spring-controlled lever pivoted on the sensitive material holder, a shield thereon adapted to overlap the graduated disk so that it cannot be read until the said lever is operated, which causes removal of the punches, two traversing rods, pawls on the sensitive material holder engaging said rods, and a lever having a V-shaped slot engaging the said pawls to withdraw same, substantially as described herein: 105

17. In a photographic type-composing machine of the class described, the combination with a roll of sensitive film, of a roll holder, a graduated disk, a pair of rollers actuated thereby and engaging the sensitive film, a spring controlled lever pivoted on the roll holder, two traversing rods, pawls on the roll holder engaging said rods, a lever adapted to disengage the said pawls, dies engaging the edges of the sensitive film, and punches operated in conjunction with said dies by the movement of the aforesaid spring controlled lever, substantially as described herein.

18. In a photographic type-composing machine, the combination with a negative disk, a camera, and a movable sensitive material holder, of a spacing cam, pins thereon of a length dependent upon the width of a corresponding character on the negative disk,

means for introducing at a suitable point in the optical system, a design tint, which it is desired to impart to the characters produced, whereby the combined images of character 5 and tint are simultaneously impressed upon the sensitive material.

19. In a photographic type-composing machine, the combination with a negative disk, a movable lens carrier, and a movable sensitive material holder, of a spacing cam, pins thereon of a length dependent upon the width of a corresponding character on the negative disk, means connecting the said pins with the sensitive material holder, a 15 crank and cam mechanism for connecting together the negative disk, the lens carrier and the sensitive material holder, means for introducing at a suitable point in the optical system a design tint, which it is desired to 20 impart to the characters produced, whereby the combined images of character and tint are simultaneously impressed upon the sen-

sitive material, and means for tilting said tints so that designs of varying angle may be imparted by a single tint. 25

20. In a photographic type-composing machine of the class described, the combination with a frame, of spools adapted to carry a series of negatives of suitable tints, milled heads for turning the spools, a mounted 30 tube for the said frame graduated with angular divisions for the purpose of setting the angle of the tint, a support for the mounting tube allowing it to be rotated, and means for subsequently fixing the said tube 35 in its support.

In testimony whereof I have signed my name to this specification in the presence of two subscribing witnesses.

ALFRED EDWIN BAWTREE.
